UNITED STATES PATENT OFFICE.

BENJAMIN H. MULL, OF CLEVELAND, OHIO.

AIRPLANE.

1,335,852.

Specification of Letters Patent.

Patented Apr. 6, 1920.

Application filed April 5, 1918. Serial No. 226,799.

To all whom it may concern:

Be it known that I, BENJAMIN H. MULL, a citizen of the United States, residing at Cleveland, in the county of Cuyahoga and State of Ohio, have invented a certain new and useful Improvement in Airplanes, of which the following is a full, clear, and exact description, reference being had to the accompanying drawings.

10 This invention relates to airplanes having for its general object the provision of simple and efficient construction thereof. The more particular object of this invention is to provide, in addition to the usual propelling means, a means adapted to exert a strong upward pull to assist in rising quickly from the ground and in sustaining the machine in the air, and to render alighting less dangerous. The method of accomplishing 15 these objects will become apparent in the following description, relating to the drawings, and the essential characteristics are summarized in the claims.

Referring to the drawings, Figure 1 is a 20 side elevation of my airplane; Fig. 2 is a plan of the same; Fig. 3 is a front elevation of the airplane; Fig. 4 is an enlarged sectional detail in plan showing the fan beneath the opening in the wing; Fig. 5 is a 25 transverse section through a portion of the plane adjacent to the opening, illustrating the fans beneath the same; Fig. 6 is an enlarged detail of the central portion of the fan members showing the connection with 30 the driving device for rotating the fans in opposite directions, and illustrating the driving connection between the engine shaft and the propeller.

Designating the parts by the use of reference numerals, the main horizontal frame 35 comprises longitudinal members 1, connected at their forward ends as at 3, and extending inwardly and connected at their rearward ends as at 4. An auxiliary transverse frame comprises a transverse member 6, longitudinal members 7 and a cross member 8, connected with rearwardly extending members 9 meeting corresponding members 10 forming parallel A-frames supporting a 40 horizontal rudder shaft 12. Rising from the frame members 6 and 7 are upright struts 14 and 15 secured to an arcuate plane 20 substantially parallel with the forward and aft dimension of the frame and curved 45 downwardly at each side thereof. The main plane is additionally supported by brace

bars 22 and tension members 24 are secured to the outer ends of the plane and to the frame members 7. Below the frames 1 and 7 are suitable downwardly extending bearing supports 25 and 26 supporting respectively a forward wheel 27 and two separated rear wheels 28.

A suitable motor, the frame or casing of which is indicated at 30, may be mounted in 60 the main frame, forward of an operator's box-like carriage 32 having a suitable seat 33 at the rear portion thereof. The usual propeller indicated at 35 may be driven from the motor by suitable mechanism shown as 65 comprising an engine shaft 36 extending rearwardly through a bearing 37 in a substantially spherical frame housing 40. On the inner end of the shaft 36 is a bevel gear 38 meshing with a similar bevel gear 39 on a vertical shaft 42 having a bearing at 43 on the lower portion of the housing 40. The gear 39 also meshes with the bevel gear 44, whose axis is parallel with the shaft 36, and mounted on the shaft 45 extending through 70 a bearing 46 in the housing and rearwardly through the bearing member 4 and carrying the propeller 35.

The altitude and direction of the plane 75 may be controlled in substantially the usual manner by rudders 50, carried on a sleeve 51 rotatably embracing the shaft 12, and standing normally in horizontal position from which they may be tipped as desired 80 by operation of a suitable pedal 52 on a shaft 53 extending transversely of the operator's box adjacent the seat thereof. On each end of this shaft 53 is a lever 54, the 85 opposite ends of which are connected to a flexible member 47 extending over a sheave 90 55 mounted on the member 9 of the A-frame adjacent to vertical bracing struts 56. This sheave is rigid with a rock shaft 57 having an offset crank arm 58 engaging the under side of the rudder plane 50 and operating in 95 a suitable slot formed by the use of a strap 59 secured to the underside of the rudder planes. As the pedal 52 is rocked, the sheave and rock shaft are rotated, through the connections described, raising or lowering the 100 forward end of the rudder planes as desired. Pivoted at the central portion of the rudder shaft between the planes 50 is a substantially 105 vertical rudder plane 60 rotating about the pivot 61, and connected with a flexible member 63 guided over suitable pulleys as shown to a sheave 65 at the lower end of suitable 110

steering column 66 carrying a steering wheel 68, the connections between the steering column 66 and the sheave being in the nature of a universal joint indicated at 69.

5 The airplane, as so far described, is intended to operate in substantially the usual and well known manner, but the essential feature of this invention is the provision of mechanism for producing a vacuum at the 10 upper side of a plate carried by the frame, and at the same time forcing air outwardly beneath the downwardly curved ends of the plane 20; thereby producing a supporting upward component. The mechanism for accomplishing this will now be described.

Between the gears 38 and 44 and within the housing 40 is a fourth bevel gear 70, mounted on a vertical hollow shaft or sleeve 71 having a bearing 72 in the upper portion 20 of the housing 40 and extending upwardly through a bearing 73 carried by a substantially circular plate 74 shown as supported on struts 75 extending upwardly from the main frame members to the plate. This 25 plate is additionally braced to securely hold it in horizontal position at right angles to the axis of the fan shafts by braces 76 extending from the rear portion of the plate to the struts 75. This plate 74 is mounted 30 a short distance beneath the plane 20 through which is made a large circular opening 77. Directly above the plate on the hollow shaft 71 is rigidly mounted a fan member comprising laterally extending 35 somewhat curved blades 78 preferably made of one integral piece having an enlarged portion at the hub secured by bolts 79 extending through flanges 80 of a metallic hub member keyed to the shaft 71. The surfaces of the blades 78 are preferably vertical at all points. A similar pair of blades 82 are mounted on a metallic hub member 83 rigidly keyed to the upper portion of the shaft 42 and secured by suitable nuts 84. 45 Short non-friction sleeves 81 may be used between the concentric shaft 42 and the sleeve shaft 71 at the upper and lower ends of the latter shaft.

It will be seen that rotation of the shaft 50 36 will drive both the gears 39 and 70 and the gear 44, the latter revolving the propeller 35 while the gears 39 and 70 rotate in opposite directions revolving the blades 78 and 82, respectively, in opposite directions. As these blades are rotating in the direction of the arrows shown in Fig. 2 at a very high rate of speed air is thrown outwardly forcibly over the plate 74 and against the downwardly curved portions of 55 the wing 20. A very pronounced vacuum is thus produced by these blades creating a strong upward pressure of air on the under side of the plate 74, at the same time the air thrown outwardly by the fan is replaced by 60 air passing through the opening 77 in the

plane. It is believed that the production of this vacuum and the forcing of the air outwardly against the downwardly curved portions of the planes in this manner may provide a very powerful supporting component 70 thereby accomplishing the objects above set forth.

It will also be seen that the method of supplying the power to the propeller and to the fans 78 and 82 is unique and effective, 75 accomplishing both the proper direction for the driven members and the even balancing of the power transmitted within the housing 40.

The purpose of using a plurality of fan 80 blades rotating in superimposed planes in opposite directions, is to eliminate the tendency of the resistance to rotate the entire airplane, although it is to be understood that these oppositely rotated blades may be 85 placed at different points beneath openings in the plane 20 or only one of them may be used in the position shown, providing other means is used to overcome the tendency of the plane to spin about the axis of the rotation of the fan. 90

Having thus described my invention what I claim is:

1. The combination in an airplane, of a main frame and motor carried thereby, a 95 supporting plane substantially parallel with relation to the direction of travel and having an opening, a fan driven by the motor and rotatable on a substantially vertical axis, the blades of the fan being also substantially vertical, and a plate below the fan for preventing air approaching the fan from below. 100

2. In an airplane, the combination with a frame and a supporting plane having a 105 downwardly curved surface and an opening through the plane, said plane being substantially parallel with the direction of travel, a fan revolving beneath the opening adapted to force air against said curved surface, and means preventing air being drawn upwardly to the fan. 110

3. In an airplane, the combination with a frame and motor, of a supporting plane, a fan substantially parallel with said plane 115 and beneath the same and adapted to force air outwardly along the plane, said plane being curved in one direction only downwardly into the path of said air, a plate beneath said fan, and means for driving said 120 fan by the motor.

4. In an airplane, the combination with a frame, motor and propeller, of a supporting plane having an opening therethrough, a fan beneath the opening driven by the motor 125 on substantially vertical axis and arranged to force air outwardly only along the underside of the plane, said plane being curved downwardly into the path of the air from said fan and having all parts of its surface 130

parallel with the direction of travel of the plane as moved by the propeller, said opening being arranged to allow air to flow therethrough to the fan, and means preventing air approaching the fan from beneath.

5. The combination in an airplane, of a frame, a supporting plane having an opening, a motor and a propeller, a plurality of 10 fans beneath the supporting plane opposite the opening and rotatable in both directions

on an upright axis, concentric shaft members for said fans, a bevel gear on each of said shaft members and a bevel gear driven by the motor meshing with each of said 15 bevel gears thereby driving them in opposite directions, and a fourth bevel gear meshing with each of the fan gears and arranged to drive the propeller.

In testimony whereof, I hereunto affix my 20 signature.

BENJAMIN H. MULL.
